WINDOW CONSTRUCTION (WIDTHWISE
ADJUSTABLE GUIDE)

Roy T. Axe, Syracuse, N. Y., assignor, by mesne assignments, to The Syracuse Trust Company, Syracuse, N. Y., a corporation of New York, trustee

Application April 17, 1933, Serial No. 666,429

13 Claims. (Cl. 189—73)

This invention relates to window frame and sash constructions particularly applicable for vehicles as railway cars, busses and the like, and has for its object very simple and economical means for adjusting the frame to variations in the widths of standard sashes, and to misalignments of the post, or the sash out of the vertical. Another object is adjusting means, which are readily accessible without removing the sash.

10 Another object is an adjustable sash guide which includes a base flange overlying or opposed to the side of the post structure which faces the edge of the sash and an angular flange lapping the inner side of the post structure, that is, the 15 side toward the interior of the car, and means coacting with or interposed between one of said flanges and the post structure for adjusting the guide member edgewise relatively to the sash.

The invention consists in the novel features 20 and in the combinations and constructions hereinafter set forth and claimed.

In describing this invention, reference is had to the accompanying drawings in which like characters designate corresponding parts in all 25 the views.

Figure 1 is an elevation of a car structure embodying my invention.

Figure 2 is a view looking to the right in Figure 1, the lower window sash being removed.

30 Figure 3 is an enlarged transverse sectional view through a post structure, the contiguous portions of the sashes on opposite sides of the post being also shown.

Figure 4 is a sectional view on line 4—4, Figure 35 3.

Figure 5 is a fragmentary sectional view, partly in elevation, taken on line 5—5, Figure 1.

Figure 6 is a detail view of one of the reinforcing blocks of the guide member.

40 Figure 7 is a transverse sectional view of a modified form of means for holding the guide member in its widthwise adjustment and taken on line 7—7, Figure 8.

Figure 8 is a fragmentary elevation, partly in 45 section, of the guide member and contiguous portion of the post structure showing a different form of means or cam for effecting the widthwise adjustment of the guide member, relatively to the sash.

50 Figure 9 is a fragmentary elevation, partly in section, of parts seen in Figure 8, looking to the right.

Figure 10 is a fragmentary transverse sectional view of a guide and sash construction embodying 55 another slightly modified form of the invention.

Figure 11 is an elevation of parts seen in Figure 1 with the facing strip removed.

Figure 12 is a cross sectional view through a post structure showing another embodiment of the adjustable guide member, contiguous portions of the sash being also shown.

Figure 13 is a fragmentary elevation of parts seen in Figure 12 looking upward, the sash being removed.

Figure 14 is a fragmentary elevation looking to the left in Figure 12.

Figure 15 is a view similar to Figure 12 of another embodiment of the adjustable guide means, contiguous portion of the sash being omitted.

Figure 16 is a fragmentary elevation looking upwardly in Figure 15.

Figure 17 is a cross sectional view through the post structure showing another slightly modified form of the invention.

Figure 18 is a fragmentary elevation of parts seen in Figure 17, looking to the left, the window sash being omitted.

Sashes for railway cars and motor busses are furnished by a sash manufacturer to fit the standard window openings of railway cars and busses, and the sash manufacturer also furnishes sash guides to be applied to the post structure, or window frame. The window openings vary within small limits, and also the sashes may vary within small limits. Likewise, the 80 posts may be slightly out of vertical alinement, and the object of this invention is a structure whereby the sash manufacturer also supplies the guide member, and the guide member is so constructed that it can be adjusted for widthwise 85 variations and for slight misalignments out of the vertical in the post structure.

This window and sash construction comprises generally a structure having a window opening, a sash guide member carried by said structure at one side of the window opening, a sash movable along the guide member and means for adjusting the guide member edgewise relatively to the sash and for holding or fixing the guide member comparatively rigidly in its adjusted position. For brevity's sake, the portions of the frame confining the window opening are referred to herein as a post or post structure, although it will be understood that in many instances, the frame member carrying the sash guide may not be strictly what is generally known as a post or post structure. The purpose of adjusting the guide member edgewise and fixing it in its adjusted position is to make the guide member conform to widthwise variations in the 90 95 100 105 110

sashes or in the posts or both or in this alignment out of the vertical of the posts or edges of the sashes.

1 designates the window frame including the 5 post structure 2. The post structure here shown includes a T-shaped body 3 having applied thereto on opposite sides of the leg of the T strips 4 bent to form one side and the bottom of a channel 5. These strips are secured to the 10 post body 2 in any suitable manner as by screws 6.

In the illustrated embodiment of my invention, the post structure further includes a facing strip 7 which is removable and which forms 15 one side of the channel 5. The post structure here shown is an intermediate one between two window sashes with a sash on each side thereof and the facing strip is double.

8 designates a sash guide member located in 20 each channel 5 and adjustable toward and from the bottom of the channel and edgewise relatively to the sash 9. The guide member here illustrated is formed of sheet metal to have a body 10 U-shaped in cross section with the sides 25 of the U coacting with the sides of the channel 5, and with the intermediate or bottom part of the U formed with an outwardly extending flange 11 for entering a groove in the edge of the sash 9. The groove in the edge of the sash is provided with a U shaped weather strip, or lining 30 12 therein coacting with the flange 11. The arrangement of the guide flange 11 in the groove of the sash per se forms no part of this invention which relates primarily to the widthwise 35 adjustable feature of the guide member 8. The guide member 8 is provided with reinforcing blocks 14 therein at intervals.

The means for adjusting the guide member 8 edgewise of the sash comprises adjusting screws 40 15 carried by the guide member and thrusting against the bottom of the channel 5 and extending in a direction edgewise of the sash. The screws have slotted heads 16 accessible from the face of the body 10 toward the edge of the sash. 45 By turning the screws in the proper direction, the guide member will be pushed outwardly, and by turning them in the other direction, the guide member can be pushed inwardly toward the bottom of the channel until the inner ends of the 50 screws bottom on the channel. The inner ends of the screws are provided with seats or disks 17 in order to have a large seating surface on the bottom of the channel. These adjusting screws are made accessible by raising the sash to make a lower adjusting screw accessible, an 55 upper adjusting screw being accessible when the sash is lowered.

The guide member 8 is held from shifting movement after being set, by the clamping action 60 of the facing strip 7. The clamping action of the strip 7 on the guide member 8 applies a binding action on the adjusting screws 15 tending to hold them from turning, or in their adjusted position. These facing strips are secured 65 to the post body 2 by means of screws 18 extending through the facing strips into threaded blocks 19 secured in any suitable manner to the end of the T formation of the body 2. These blocks 19 are here shown as provided with bifurcated bases as 21 extending astride the edge of the leg of the T formation and secured thereto as by rivets or screws 22.

The reinforcing blocks 14 are also formed with recesses 24 located on opposite sides of the flange 70 11 for the purpose of receiving the bifurcated

ends of the bolt of a sash holder. This feature forms no part of this invention.

In Figures 7, 8, and 9, another embodiment of the widthwise adjustable guide member is shown. 80 30 designates a wood post. 31 is a sheet metal window frame part, angular in cross section, attached to the post as by screws 32 and corresponding to the strip 4, Figures 3 and 4.

33 is the facing strip corresponding to the strip 7, Figures 1, 2, 3, and 4. 34 is the guide member in the channel formed by the strips 31, 33. In this embodiment of the invention, the guide member 34 is adjusted by means of a rotary cam 35 carried by the strip 31 on the bottom of the channel formed by this strip and the facing strip 33. The cam 35 is discoidal in general form with a polygonal periphery shaped to receive a wrench, and is formed with a cam surface 36 which is provided on one side of the disk and coacts with a follower 37 on the guide member. The cam 35 is secured to the strip 31 or the portion or flange forming the bottom of the channel by suitable means as a rivet 38. There are a plurality, usually two cams, located 95 toward the lower and upper ends of the guide member. The guide member is formed up of sheet metal and is practically the same as that shown in Figure 3, except that the foiced portion 39 corresponding to the part 11, Figure 3, has its side portions spaced apart to receive a plate 100 40 on which the follower 37 is provided. One of the walls of the face portion of the guide member 31 is provided with an opening or openings 41 through which the cams can be adjusted by means of a wrench.

The facing strip 33 is removable for the purpose of adjusting the cams 35 through the openings 41. The facing strip 33 is held in position by means of screws 42 extending through openings 43 in the facing strip and threading into 115 nuts 44 located in recesses or boxes 45 provided on the bottom portion of the strip 31. These nuts are threaded at one end only and have a counterbore 46 opening through their other or inner ends. After the screws are initially located in the nut their inner ends are spread or split, as at 47, so that the screw can not be entirely removed from the nuts and lost. The openings 43 are slots opening through the edge of the facing strip toward the post body. A 120 lock washer 48 is located between the outer end of the nut and one end wall of the box or recess 45. The nut is long enough to bottom on the other end wall of the box at 49 when the screw 42 is loosened sufficiently to permit the removal 125 of the strip 33. This feature holds the screw in alignment, or from assuming an inclined position when loosened, so that the strip 33 can be readily replaced. When the adjustment of the 130 cams has been effected, the strip 33 is replaced by an edgewise movement passing the slots 43 over the shanks of the screws 42 under the heads of the screws and the screws tightened thus 135 clamping the face plate 33 against the guide member 31.

In Figure 10, a structure is shown in which the sash guide member is shiftable laterally from the edge of the sash far enough to let the sash be removed, the guide member being assembled as a unit with the sheet metal strips which 140 are applied to the post structure.

50 designates the edgewise adjustable guide member, this being formed up of sheet metal to have a base portion 51 consisting of front and rear flanges 52, 53 and a guide member or lip 145

extending into the channel 54 in the edge of the sash 55.

56 designates the sheet metal strips which are applied to the post structure 57 which is shown as a T-shaped angle iron or of the form shown in Figure 3. This strip 56 is provided with a right angular portion including a flange 58 and a flange 59 which overlies the leg of the T formation and is secured thereto in any suitable manner as by screws 60. The flange 58 and a removable facing strip 61 form opposing sides of a channel in which the base of the adjustable guide member is mounted. The adjustable guide member is secured to the strip 56 or the flange

10 58 thereof by means of the screw and nut 62, 63, the screw extending through a slot 64 in the flange 58 which permits the guide member 51 to be shifted toward the post far enough so that the guide member can entirely clear the sash

15 55 and permit the sash to be removed without removing the guide member. In order to prevent complete removal of the screws, the ends of the screws are expanded or riveted over in any well known manner so that the screws cannot

20 26 entirely thread out of the nuts. There is a plurality of these screws 62 and it is obvious that the guide member 51, after being properly positioned, can be permanently held in this position by tightening the screw 62 and the screws may take

30 35 any one of a plurality of positions along the slot 64. The flange 53 of the guide member is provided with suitable work holes 67 at intervals for permitting access to the heads of the screws 62.

40 After the guide strip has been secured in its adjusted position, the base plate 61 is applied and tightened by means of the screw 68 against the flange 53.

In Figures 12, 13 and 14, 70 designates a wood post structure, 71 a sash guide member adjustable edgewise relatively to the sash 72, the guide member 71 being shown as including a base plate having a rib 73 extending into the channel or groove in the edge of the sash. The base plate 45 also has an angular flange 74 overlapping the inner face of the post 70. The means for adjusting the guide member 71 edgewise relatively to the sash, as here shown, includes a screw 75 threading into the post and having its head underlying the base flange of the guide member 71, the screw being accessible through a work hole 76 in the base plate, which work hole is of less diameter than the head of the screw so that by backing out the screw by means of a screw driver 50 extending through the work hole, the sash guide member 71, the head of the screw thrust outward against the guide member and adjusts or shifts or locates it a predetermined distance edgewise away from the post and by screwing the screw 55 inward through the work hole, the sash guide member can be shifted edgewise toward the post against the head of the screw. The screw illustrated at the right hand side of Figure 12 threads into a metal bushing or insert 77 in the post 70. 60 The screw illustrated at the left hand side of the post of Figure 12 is a wood screw and threads directly into the post. There are a plurality of adjusting screws, two being usually sufficient, located near the lower and upper ends of the guide member.

65 After being adjusted by means of the screws 75, the sash guide member is tightened by means of screws 79 extending through the base plate and threading into the post and tending to tighten the base plate against the head of the screw and

thus hold the base plate from shifting and also indirectly hold the screw 75 from turning by creating a binding action on the screw 75 sending to hold it from turning. As here shown, there is a screw 79 located above and below each screw 75.

80 85 80 is a face plate corresponding to the face plate 7 (Figure 1) and is held in position in any suitable manner.

90 95 90 In Figure 15, 81 designates a post; 82 the guide member on each side of the post, this including a base plate having an angular flange 83 lapping the inner side of the post. The guide member is adjustable edgewise relatively to the sash and held in its adjusted position by one or more screws 84 extending through a slot 85 in the flange 83 and threading into the post and having its head large enough to cover the slot in all widthwise adjustments of the guide member 81. To adjust the guide member, the screws are loosened and the guide member is shifted inwardly or outwardly the desired distance, the slots permitting such sliding and then the screw tightened firmly clamping the guide member in its adjusted position. In both Figures 12 and 15, the guide member on the right hand side of said figures are shown as differently adjusted from those on the left hand side. In any of the constructions, the screws 15 (Figure 3), cams 35 (Figure 8) and screws 75 (Figure 12) are rotary members operating on the inclined plane principle and coacting with the post structure and operable in a direction edgewise of the sash to adjust the sash guide widthwise.

100 105 100 In both Figures 12 and 15, the guide member on the right hand side of said figures are shown as differently adjusted from those on the left hand side. In any of the constructions, the screws 15 (Figure 3), cams 35 (Figure 8) and screws 75 (Figure 12) are rotary members operating on the inclined plane principle and coacting with the post structure and operable in a direction edgewise of the sash to adjust the sash guide widthwise.

110 115 110 In Figure 17, a widthwise adjustable sash guide is shown in which the sash slides in a sash guide groove formed in the widthwise adjustable guide member and the guide member is adjusted by means quite similar to that shown in Figure 3. In Figure 17, 86 designates a sheet metal window frame member secured to the post 87 and 88 a face plate removably secured to the window frame member 86, as by screws 88^a extending through slots in an angular base flange of the plate 88 and threading in the base of the post member 86. The slots permit the face plate to be snugly placed against the adjustable member 89 to be now described. The window frame member 86 and the face plate forms a channel of which the face plate 88 constitutes a removable side. 89 designates a widthwise adjustable guide member located in the channel formed by the frame member 86 and the face plate 88, this enclosing or housing a filler or strip 90 of non-metallic or fibrous material, as felt, formed with 120 125 120 a groove 91 in which the stile 92 of the window sash 93 slides. The member 89 is adjustable widthwise without being under pressure, as spring pressure, by adjusting means similar to the screws 15 shown in Figure 3. 94 designates one 130 135 130 of the adjusting screws threading at 95 through the bottom of the guide member 89 and thrusting at their inner ends against the bottom of the channel formed by the guide member 86 and face plate 88 and having their outer ends exposed through the bottom of the guide groove in the felt or fibrous filler 90, the outer end of each screw being provided with a screw-driver slot 96. By manipulating the sash, that is, raising or lowering it, so as to expose the screws, the 140 145 140 screws can be turned to adjust the guide channel widthwise of the sash. There are usually two adjusting screws located respectively near the upper and lower ends of the guide and so located that by raising the sash, the lower screw is ex-

150

posed; and when the sash is closed, the upper screw is exposed. Obviously, by turning the screws in one direction or the other, by means of a screw-driver, the guide member 89 and parts carried thereby, can be adjusted toward or from the post and different ends of the guide member 89 can be adjusted differently to conform to inaccuracies and misalignments.

In operation, the manufacturer supplies the sash and the sash guide and also may supply the sheet metal parts 4 and 7 which are applied to the post body. The car manufacturer secures the parts 4 to the post body 2 and inserts the guide members 8 adjusting them by means of the screws 14 to the proper position in the channel 5. The facing strip 7 is then applied and tightened by means of the screws 18 which clamp the facing strip against the guide member with enough pressure to hold the guide member from sliding with the sash when the sash is being raised and lowered.

This construction is particularly economical in manufacture, readily applied to the post body, and by this construction the window frame is readily adjustable to variations that may exist in the widths of the sashes, or in the spacing of the posts, and to slight misalignments out of the vertical.

What I claim is:

1. In a window and sash construction, a frame including a post structure, a sash guide member carried by the post structure, a sash movable along the guide member, the guide member being adjustable relatively to the post structure and the sash in a direction edgewise of the sash, and means self-contained with the guide member for adjusting the guide member to conform to variations in the widths of sashes and vertical misalignments of the post structure, said means including screws threading in the guide and thrusting against the post structure and extending in a direction edgewise of the sash.

2. In a window and sash construction, a frame including a post structure formed with a lengthwise channel, the post structure including a body and a facing strip forming one side of the channel, a sash guide member mounted in the channel, a sash movable along the guide member and slidably interlocked therewith, the guide member being adjustable toward and from the bottom of the channel, means for adjusting the guide member in the channel edgewise relatively to the sash, and means securing the facing strip to the body and clamping the facing strip against the guide.

3. In a window and sash construction, a frame including a post structure formed with a lengthwise channel, a guide member having a base portion in the channel and a flange extending out-side of the channel, a sash coacting with the guide member, the flange extending edgewise of the sash, and the sash having a groove in its edge for receiving the flange, the guide member being adjustable in the channel edgewise relatively to the sash, and means for adjusting the guide member edgewise relatively to the sash and holding it in its adjusted position, said means including screws carried by the guide member and thrusting against the bottom of the channel and threading into the guide member, the screws extending in a direction edgewise of the sash and having their heads accessible on the side of the guide member toward the edge of the sash and on one side of said flange.

4. In a window construction a frame including

a post formed with a lengthwise channel, a guide member mounted in the channel, a sash movable along the guide member, the guide member including a base U shaped in general form with the branches of the U engaging opposite sides of the channel, reinforcing blocks in the U shaped base, screws threading in the blocks and thrusting against the bottom of the channel, the screws having heads accessible from the side of the base toward the edge of the sash.

5. In a window and sash construction, a frame including a post structure, a sash guide member carried by the post structure, a sash movable along the guide member, the guide member being adjustable relatively to the post structure and the sash in a direction edgewise of the sash, and means for adjusting the guide member to conform to variations in the widths of sashes and vertical misalignments of the post structure, said means including screws threading through the guide member and thrusting against the post structure and extending in a direction edgewise of the sash, and having heads accessible from the side of the guide toward the edge of the sash, whereby the adjusting screws are self-contained with the guide member and thrust only against the post structure.

6. In a window sash and guide construction, a frame, a post member, a guide member carried by the post member, a sash movable along the guide member, the guide member being adjustable relative to the post member and the sash in a direction edgewise of the sash, and means carried by and self contained with one of said members and coacting with the other of said members, and operable to adjust the guide member relative to the post member to conform to variations in the widths of sashes and vertical misalignments in the post member, said means including screws threading in one member and coacting with the other, whereby upon turning of the screws, the guide member is shifted edgewise relative to the post member, said screws extending in a direction edgewise of the sash, and locking means operable to hold the guide member in its adjusted position.

7. In a window and sash construction, a frame, a post member, a guide member carried by the post member, a sash movable along the guide member, the guide member being adjustable relative to the post member and the sash in a direction edgewise of the sash, and means carried by and self contained with the guide member and coacting with the post member, and operable to adjust the guide member relative to the post member to conform to variations in the widths of sashes and vertical misalignments in the post member, said means including screws threading in one of said members and coacting with the other, whereby upon turning of the screws, the guide member is shifted edgewise relative to the post member, said screws extending in a direction edgewise of the sash, and locking means for holding the guide member in its adjusted position.

8. In a window sash and guide construction, a frame, a post member, a guide member carried by the post member, a sash movable along the guide member, the guide member being adjustable relative to the post member and the sash in a direction edgewise of the sash, and means carried by and self contained with one of said members and coacting with the other of said members, and operable to adjust the guide member relative to the post member to conform to variations in the widths of sashes and vertical misalignments in the post member, said means including screws

- threading in one member and coacting with the other, whereby upon turning of the screws, the guide member is shifted edgewise relative to the post member, said screws extending in a direction edgewise of the sash, and means acting on the guide member to create a binding action on the adjusting screws and hold the guide member and the screws in their adjusted position. 5
9. In a window and sash construction, a frame, 10 a post member, a guide member carried by the post member, a sash movable along the guide member, the guide member being adjustable relative to the post member and the sash in a direction edgewise of the sash, and means carried by 15 and self contained with one of said members and coacting with the other of said members, and operable to adjust the guide member relative to the post member to conform to variations in the widths of sashes and vertical misalignments in 20 the post member, said means including screws threading in one of said members and coacting with the other, whereby upon turning of the screws, the guide member is shifted edgewise relative to the post member, said screws extending 25 in a direction edgewise of the sash, and means acting on the guide member to create a binding action on the adjusting screws, and hold the guide member and the screws in their adjusted position, said locking means including screws 30 extending through the guide member in a direction edgewise of the sash, and when tightened acting to create a binding action on the adjusting screws, and thereby holding the guide member and the adjusting screws in their adjusted 35 position. 10. In a window and sash construction, a frame including a post member, a guide member carried by the post member, a sash movable along the guide member, the sash and the guide member 40 having coacting means for holding the sash and guide member out of sliding metal to metal contact, the guide member being adjustable relative to the post member and the sash in a direction edgewise of the sash, and means self contained with and carried as a unit with one of 45 said members, and operable to adjust the guide member to conform to variations in widths of the sashes and vertical misalignments of the post structure, said means including screws threading in one of said members and coacting with the other, whereby upon turning of the screws the guide member is adjusted edgewise relative to the post member, said screws extending in a direction edgewise of the sash, and means for locking the guide member and the adjusting screws in their adjusted position. 55
11. In a window and sash construction, a frame including a post member, a guide member carried by the post member, a sash movable along the guide member, the sash and the guide member having coacting means for holding the sash and guide member out of sliding metal to metal contact, the guide member being adjustable relative to the post member and the sash in a direction edgewise of the sash, and means self contained with and carried as a unit with said guide member, and operable to adjust the guide member to conform to variations in width of the sashes and vertical misalignments of the post structure, said means including screws threading in one of said members and coacting with the other, whereby upon turning of the screws the guide member is adjusted edgewise relative to the post member, said screws extending in a direction edgewise of the sash, and locking screws extending in a direction edgewise of the sash, said screws extending into the guide member and creating, when tightened, a binding action on the adjusting screws, and lock the guide member and the adjusting screws in their adjusted position. 80
12. In a window and sash construction, a frame including a post structure, the post structure including a body and a strip separable from the body, a guide member carried by the post member, the guide member being adjustable in a direction edgewise of the sash relative to the post structure, means for adjusting the guide member, said strip coacting with the guide member to hold it in its adjusted position, said strip, and the means for securing it to the body of the post structure, constituting means coacting with the 100 guide member for holding it in its adjusted position. 105
13. In a window and sash construction, a frame including a post structure including a body, a demountable facing strip, and means for securing the facing strip to the body, a guide member coacting with the post structure, a sash movable along the guide member and slidably interlocked therewith, the guide member being adjustable in a direction edgewise of the sash relative to the 110 post structure, means for adjusting the guide member including screws threading in the guide member in a direction edgewise of the sash, and having heads accessible when said strip is removed, said strip coacting with the guide member, and the strip, and the means for securing it to the post structure, constituting means for holding the guide member in the position to which it has been adjusted by the screws. 115 120 125
